William Angus Corley

UNITED STATES PATENT OFFICE.

WILLIAM ANGUS CORLEY, OF WASHINGTON, DISTRICT OF COLUMBIA, ASSIGNOR TO
THE GOVERNMENT OF THE UNITED STATES.

CIRCUIT-BREAKER.

1,295,007.

Specification of Letters Patent. Patented Feb. 18, 1919.

Application filed April 26, 1918. Serial No. 230,992.

To all whom it may concern:

Be it known that I, WILLIAM ANGUS CORLEY, a citizen of the United States, and a resident of Washington, District of Columbia, have invented certain new and useful Improvements in Circuit-Breakers, of which the following is a specification.

This invention relates to circuit breakers, and more particularly to devices adapted to be used in submerged naval mining operations for automatically breaking the circuit, as for example, between a shore station and a mine should the mine accidentally sink to a point where its explosion might damage the communicating wires to other mines.

It is, therefore, one of the objects of the present invention to provide an inexpensive circuit breaker having relatively few parts which may be inexpensively manufactured, easily assembled and adapted to automatically break the circuit under abnormal condition. A further object is to provide a device of the above character of simple and practical construction particularly adapted for submerged work.

Other objects will be in part obvious from the annexed drawings and in part indicated in connection therewith by the following analysis of this invention.

This invention accordingly consists in the features of construction, combination of parts and in the unique relations of the members and in the relative proportioning and disposition thereof; all as more completely outlined herein.

To enable others skilled in the art so fully to comprehend the underlying features thereof that they may embody the same by the numerous modifications in structure and relation contemplated by this invention, drawings depicting a preferred form have been annexed as a part of this disclosure, and in such drawings, like characters of reference denote corresponding parts throughout all the views, of which:

Figure 1 is a longitudinal sectional view of the complete device; Figs. 2 and 3 are detail views showing the ends of the inclosing shell and base of the hook and eye respectively.

Referring now to the drawings in detail, 5 denotes any suitable form of attaching

member, as, for example, a hook preferably made of copper or other non-corrodible metal of high conductivity, which it may be 55 assumed is adapted to be physically attached to an anchor at the bottom of a harbor and electrically connected to a shore station. At the opposite end of the device is a second attaching means 6, of similar material, which 60 may be in the form of a ring or eye. It may be assumed that this is attached to a mine both physically and electrically. It will be noted that the base of the hook member 5 is provided with an adjustable contact point 7 65 molded in a cup-shaped insulating member 8 of condensite, or the like, which member is closed at its upper end by an insulating plug 10 of similar material, molded around a steel bushing 11, in which is threaded for adjustment a second contact point 12, the opposite end of which is electrically connected with the copper ring 6 through its surrounding stem.

The cup-shaped member 8 is adapted to 75 hold a certain quantity of mercury or the like 14 adapted to complete the circuit between the two contact points 7 and 12 when the device occupies its normal vertical position, but which will automatically break the 80 circuit after the device has swung or tilted to a predetermined angle with respect to the perpendicular.

It will be noted that both the attaching members 5 and 6 are provided with flanged 85 over ends 15 and 16, respectively, of irregular shape to prevent turning, as shown for example in Fig. 3. These ends are held between a central body member 17 of suitable insulating and water-proofing material such 90 as stearin pitch, and end washers 18 and 20, of bakelite, for example, each provided with collars 21 surrounding the attaching means, whereby such attaching means are thoroughly insulated from each other. A two- 95 part inclosing casing 22 detachably connected in any desired manner at 23, surrounds these parts. The casing 22 is preferably made of copper to prevent the corrosive action of sea water.

One method of use and operation of a device of this character is substantially as follows:

The contact member 12 is adjusted with

respect to the contact 7 according to the amount of mercury within the cup 8, after which the adjusting opening is sealed over as by means of solder and covered with pitch 5 at the point 24. The parts are connected with the anchor and mine as desired, and so long as the mine assumes a substantially vertical position over the anchor the circuit through the circuit breaker will be completed. If, however, the mine should sink 10 for any reason, or tilt beyond a predetermined desired angle, the circuit breaker will assume a position more nearly horizontal, and thereby break the circuit automatically, thus positively preventing a discharge of the mine from the shore station, which might break or damage adjacent wires connected with other mines in the vicinity.

It is, of course, to be understood that the 20 terms horizontal and vertical as used in the specification and claims are relative and are to be understood as being applicable to a device in which the circuit breaking operation takes place where the device moves from 25 one position to a position more nearly at right angles thereto, for it is obvious that in certain operations it might be advisable to have the circuit maintained closed while the device was horizontal, and to be automatically broken when for any reason the 30 device occupied a vertical position.

The present invention is of simple and practical construction, and reliable and efficient in use and operation.

35 Without further analysis, the foregoing will so fully reveal the gist of this invention that others can by applying current knowledge readily adapt it for various applications without omitting certain features that, 40 from the standpoint of the prior art, fairly constitute essential characteristics of the generic or specific aspects of this invention, and therefore such adaptations should and are intended to be comprehended within the 45 meaning and range of equivalency of the following claims.

I claim as my invention the following:—

1. In an apparatus of the character described, in combination, a pair of oppositely disposed attaching members provided with irregular shaped collars, adjustable contact points carried by said attaching members and normally spaced apart, means for adjusting one of said contact points from within 50 out the device, a hollow insulating multi-part container surrounding said contact points, a water proof insulating compound molded around said container and said irregular shaped collars, a two-part outer casing embracing the said irregular shaped head and said container, and insulating means between said collars and said outer container.

2. In an apparatus of the character described, in combination, a pair of oppositely

disposed attaching members of high electrical conductivity, provided with irregular shaped collars, adjustable contact points carried by said attaching members and normally spaced apart, and a hollow insulating 70 container surrounding said contact points, a fluid of high electrical conductivity within said container making contact with both of said points only when said apparatus is in normal position, a casing surrounding 75 said insulating container and said collars and water-proofing means for insulating said casing from said attaching members and said container, said last-named means being molded around said irregular shaped collars. 80

3. In an apparatus of the character described, in combination, a pair of oppositely disposed attaching members provided with collars, an adjustable contact point having threaded connection with one of said members, a metallic bushing molded in the other member, a contact point threaded within said bushing and adjustable from the outer end of said second member, a hollow insulating container molded around said contact points, a water-proof covering member molded around said container and said collars, a two-part detachable casing inclosing said device, and washers insulating said collars from said casing.

4. In an apparatus of the character described, in combination, a pair of oppositely disposed attaching members of high electrical conductivity and provided with collars, a contact point having threaded connection 1 with one of said collars, an opening through said second collar, a metallic bushing secured within said collar, a contact point within said bushing adjustable from the outer end of said attaching member, a hollow insulating container surrounding said first contact point, an insulating cover member surrounding said bushing and fitting within said insulating container, a water proofing composition molded around said insulating container, water proofing composition washers disposed adjacent the outer surface of said collar, and a two-part outer casing inclosing the entire device and insulated from the attaching members by said water proofing members.

5. In an apparatus of the character described, in combination, a pair of oppositely disposed attaching members of high electrical conductivity and provided with collars, a contact point having threaded connection with one of said collars, an opening through said second collar, a metallic bushing secured within said collar, a contact point within said bushing adjustable from the outer end of said attaching member, a hollow insulating container surrounding said first contact point, an insulating cover member surrounding said bushing and fitting within said insulating container, a water proofing compo-

sition molded around said insulating con-
tainer, water proofing composition washers
disposed adjacent the outer surface of said
collar, and a two-part outer casing inclosing
5 the entire device and insulated from the at-
taching members by said water proofing
members, and means for closing said opening

in said second attaching member, said
means comprising a metallic composition
and a water proofing composition.

Signed at Washington, District of Co-
lumbia, this 16th day of April, 1918. 10

WILLIAM ANGUS CORLEY.
